UNITED STATES PATENT OFFICE.

IRVIN W. JOHNSON, OF COSMOPOLIS, WASHINGTON.

TAPER ATTACHMENT FOR SAWMILL-CARRIAGE BLOCKS.

1,383,544.

Specification of Letters Patent.

Patented July 5, 1921.

Application filed August 10, 1918. Serial No. 249,237.

To all whom it may concern:

Be it known that I, IRVIN W. JOHNSON, a citizen of the United States, residing at Cosmopolis, in the county of Grays Harbor 5 and State of Washington, have invented certain new and useful Improvements in Taper Attachments for Sawmill-Carriage Blocks, of which the following is a specification, reference being had to the accompanying drawings.

This invention relates to carriage block attachments for saw-mills, and particularly to means whereby the log to be sawed may be adjusted to an inclination with the plane 15 of the saw, so that logs may be tapered from 2 to 8 inches to get a straight grain of the timber, the device being particularly adapted for sawing spruce logs, where every clear log must be tapered.

20 The general object of the invention is to provide a very simple means to this end which may be applied to any ordinary saw-mill carriage block or knee and so constructed that the log may be adjusted 25 very quickly and yet have sufficient support for heavy logs.

A further object is to provide a device of 30 this character including a sliding abutment or block operating within the carriage block or knee and operatively connected to a lever whereby it may be shifted longitudinally, and in this connection provide a pawl for holding the sliding block from reverse movement after it has been adjusted which pawl 35 is readily disengaged from the sliding block to permit it to be pulled back when desired.

40 A further object is to provide a device of this character which will permit the use of the ordinary hook dog and lever and the usual speed dog and lever, if desired.

Other objects will appear in the course of the following description.

45 My invention is illustrated in the accompanying drawings, wherein:—

Figure 1 is a side elevation of a portion of a saw-mill carriage and carriage block or knee with my taper attachment applied thereto;

50 Fig. 2 is a vertical longitudinal sectional view of the construction illustrated in Fig. 1;

Fig. 3 is a vertical transverse section on the line 3—3 of Fig. 1;

Fig. 4 is a fragmentary section on the line 4—4 of Fig. 3; and

55 Fig. 5 is a side elevation of the knee or

carriage block showing the countersunk recess for the bearing of the pawl shaft.

Referring to these drawings, 10 designates the usual connected beams or rails, upon which the knee or carriage block 11 is adapted to slide. The base 12 of this block is illustrated as provided with the laterally extending overhanging flanges 13 engaging with the flanges of the rails upon which the carriage block slides. The carriage block is 65 also provided with its medially disposed screw-threaded extension 14 to receive the usual adjusting screw 15. All of these parts are old and well known and require no further description.

70 The carriage block or knee 11 is formed with the upwardly extending spaced supporting walls 16 and 17, formed at their upper ends with the inwardly extending ribs 18. Operating between the upper ends 75 of these walls is a steel slide 19 having its lateral faces grooved as at 20 to receive the ribs 18. This slide extends upward to the upper edge of the wall 17 and above the upper edge of the wall 16, and then extends 80 laterally over the upper edge of the wall 16 and downward upon the outer face of this wall as at 21. The rear edge of this overhanging portion 21 is cut-away as at 22. The under face of the sliding block 19 85 is provided with a plurality of ratchet teeth 23.

Extending transversely through the walls 16 and 17 below the slide 19 is a pawl shaft 24 having mounted thereon and preferably 90 cast therewith the pawl 25 adapted to engage with the ratchet teeth 23. The shaft 24 extends out through bearings 26 in the walls 16 and 17 and at one end the shaft is provided with a spring 27, which is coiled 95 around the shaft, has one end connected thereto and the other end to the corresponding bearing 26, this spring acting to rotate the shaft 24 to carry the pawl 25 into engagement with the ratchet teeth and to hold 100 it thereon.

To the opposite end of the shaft 24 is connected an arm 28 and to this arm there is connected a rod 29 having a hand-hold at its upper end whereby the shaft 24 may be 105 rocked against the force of the spring 27 to carry the pawl out of its engagement with the ratchet teeth. Bearings or bushings 26 are detachably mounted in the walls 16 and 17 so that by removing these bushings, the 110

pawl shaft and pawl may be removed or inserted. The walls 16 and 17 are countersunk, as at 26^a, for the reception of the flange of the bushing or bearing 26, as illustrated in Fig. 5.

While I have not illustrated a hook dog or hook dog lever such as is ordinarily used with carriage blocks or knees, yet it is to be understood that such a hook dog and lever will be used and that preferably a speed dog and corresponding lever will be used. I have not illustrated these devices, however, as they are well known and form no part of my invention. I have illustrated the walls 16 and 17 as being provided with a bearing 30 for the shaft of the hook dog lever, and as being formed with a bearing 31 for the shaft of the speed lever connection, and I have also illustrated in Fig. 2 a guide or passageway 32 for the speed dog itself. It will be obvious, however, that this is purely illustrative and that the block may be provided with any suitable dogs and levers for operating them and that the detailed construction of the taper attachment and the means for operating it may be modified in many ways, without departing from the spirit of the invention as defined in the appended claims.

30 For the purpose of shifting the sliding block 19, I have illustrated this block as formed with an extension 33 to which a lever 34 is operatively connected, this lever being in turn connected to the base of the knee by means of a link 35 pivoted to ears 36. As before stated I do not wish to be limited to this particular arrangement, however.

I claim:—

40 1. In a saw mill carriage mechanism, a base, a knee slidably mounted on said base, power operated means for shifting said knee longitudinally of the base, a block mounted on and carried by the knee and having sliding movement on the knee parallel to the movement of the knee and extending to the front face thereof, the block having ratchet teeth on one face thereof extending rearward, a pawl mounted on the knee and resiliently urged into engagement with the ratchet teeth and having a handle whereby it may be shifted out of engagement with the teeth, and a lever operatively mounted upon the knee and having operative connection to the block whereby the block may be advanced or retracted relative to the knee.

2. In a saw mill carriage mechanism, a base, a knee slidably engaging said base, power operated means for longitudinally shifting the knee, said knee being formed with two upwardly extending side walls, a block disposed between and slidably mounted on the side walls for movement parallel to the movement of the knee, said block extending to the front face of the knee, the

under face of the block having rearwardly facing ratchet teeth, a shaft extending through the two walls and beneath the block, a pawl mounted upon the shaft and engageable with the ratchet teeth to prevent retractive movement of the block, resilient means urging the pawl into engagement with the ratchet teeth, a lever mounted upon one end of the shaft whereby the shaft may be rocked to release the pawl from its engagement with the ratchet teeth, and a lever operatively mounted upon the knee and operatively engaging said block whereby the block may be retracted or advanced.

3. A saw mill mechanism of the character described including a base, a knee slidably engaging said base, power operated means for shifting the knee, said knee having its upper portion formed with two upwardly extending, parallel walls, a block mounted between said walls at the upper end of the knee and having longitudinal sliding engagement with the walls, said block extending to the front face of the knee and downward upon the front face of the knee to a point below the middle of the knee, the block having rearwardly facing ratchet teeth on its under face, a pawl carrying shaft extending through the two walls of the knee beneath the block, a pawl mounted thereon and engageable with the ratchet teeth, a spring on one end of the shaft rocking it in a direction to carry the pawl into engagement with the teeth, a lever on the opposite end of the shaft exteriorly of the knee whereby the shaft may be rotated to carry the pawl out of engagement with the ratchet teeth, and a lever operatively mounted upon the knee and operatively connected to the block.

4. The combination with the knee of a saw mill carriage having upwardly extending spaced walls, one of the walls being shorter than the other wall, of a block disposed between the walls and having sliding engagement therewith longitudinally of the carriage, said block extending laterally over the shorter wall and then downward over the outer face of the wall and extending downward at its forward end over the front face of the knee, manually releasable means for locking the block against rearward movement relative to the knee, and manually operable means for shifting the block longitudinally.

5. The combination with the longitudinally movable knee of a saw mill carriage having upwardly extending side walls, of a block disposed between the upper ends of the walls and having sliding engagement therewith longitudinally of the carriage, said block extending laterally over one wall and having a portion extending downward over the front edges of the two walls of the knee and having a portion extending over the outer face

- of one of said walls and connecting said downwardly extending portion with that portion of the block extending over the top of the wall of the knee, that portion of the block extending over the outside face of the knee being cut away, the under face of the block being formed with rearwardly facing ratchet teeth, a pawl shaft extending through the side walls of the knee and projecting beyond one of said side walls behind the cut away portion of the block, a lever attached to this projecting portion of the pawl shaft, a pawl attached to the pawl shaft and engaging the ratchet teeth of the block, a 10 spring urging the pawl outward in a direction to carry the pawl into engagement with the ratchet teeth, and manually operable means for longitudinally shifting the block independently of the knee.
- 15 6. In saw mill carriage mechanism, a base formed to provide spaced tracks, a knee having a base portion formed to slide upon said tracks, the base portion having an intermediate portion extending downward into the 20 space between the tracks and screw-threaded, a feed screw extending longitudinally through the space between the tracks and engaging said screw-threaded portion of the 25
- base of the knee, said knee having upwardly extending, laterally spaced walls, a block 30 slidably mounted between the upper portions of said walls for longitudinal movement parallel to the movement of the knee, said block extending to the front of the knee and having a portion extending downward 35 over the front of the knee, the under face of the block being provided with rearwardly facing ratchet teeth, a pawl shaft passing through the two walls of the knee between the block, a pawl mounted thereon and engageable with the ratchet teeth, a spring 40 rocking the shaft in a direction to carry said pawls into engagement with the ratchet teeth, a lever on the shaft exterior to one of said walls of the knee whereby the shaft 45 may be rocked to retract the pawl, and a lever operatively pivoted upon the base of the knee, the block having a member extending therefrom and pivotally engaged with said lever.
- 50 In testimony whereof I hereunto affix my signature in the presence of two witnesses.
- IRVIN W. JOHNSON.
